UNITED STATES PATENT OFFICE.

XAVER DODEL, OF SAN FRANCISCO, CALIFORNIA.

DESIGN FOR A DENTAL ELEVATOR.

SPECIFICATION forming part of Design No. 31,494, dated September 5, 1899.

Application filed June 28, 1899. Serial No. 721,990. Term of patent 14 years.

To all whom it may concern:

Be it known that I, XAVER DODEL, a subject of the German Emperor, residing in the city and county of San Francisco, State of California, have invented and produced a new and original Design for a Dental Elevator, of which the following is a specification, reference being had to the accompanying drawings, in which—

Figure 1 is a side elevation of an elevator shaped in conformity with my design. Fig. 2 is an elevation at right angles to the view shown in Fig. 1, the extension being illustrated in cross-section on the line $x-x$ of Fig. 1.

The leading features of my design consist

in an extension B, projecting from the shank A at an angle of less than ninety degrees, said extension being concave on its upper side or face and the forward and outer corner C of the junction of the shank and the extension being rounded. Furthermore, the forward end of the extension is rounded and provided with serrations or teeth D.

25

What I claim is—
The design for a dental elevator, substantially as herein shown and described.

XAVER DODEL.
